PACKAGING REEL

William H. Hawkins, Stamford, Conn., assignor
to Freyberg Bros.-Strauss, Inc., New York,
N. Y., a corporation of New York

Application September 12, 1942, Serial No. 458,093

12 Claims. (Cl. 206—51)

This invention relates to packaging reels, and more particularly, to reels of the type now used in packaging and merchandising relatively short lengths of ribbons. It is obvious that reels of the particular class must be attractive, must be capable of being readily assembled and to have the ribbon applied thereto with facility, and must be very inexpensive. It is the object of my invention to contribute to the art a reel of the class indicated, and having the particular merits listed.

The reel of my invention is of that class having a central portion on which the ribbon is actually wound, with flanges at each side of the central portion confining the ribbon therebetween. As a feature of my invention, I form the central portion of my reel separate from the flanges thereof, a further feature of my invention residing in the new and novel means utilized by me for assembling the flanges to the central portion of the reel.

As a further feature of my invention I form the central portion of my reel of an inexpensive, collapsible, box-like member about which the ribbon is wound, it being a particular feature of my contribution to the art that the ribbon itself preferably maintains the collapsible, box-like member against collapsing, so that it may form the central portion of my reel.

Still a further feature of my invention resides in the use of openings in certain surfaces of the central portion of my reel, and through which the said central portion may be rotated to wind the ribbon thereon, the openings being of such form that they may thereafter be utilized for assembling the flanges thereto. This dual function of the openings is extremely important in this highly developed art in which it is so very necessary to simplify structures in order that the finished product may be very inexpensive.

I have thus described generally the several features of my invention in order that the nature of my contribution to the art may be better appreciated. Actually, those skilled in the art will readily conceive various structures whereby the conception on which my contribution is based may be utilized, and it is therefore important that the patent claims to be granted me shall be sufficiently broad to protect me in the enjoyment of my invention.

Referring now more particularly to the drawing, Fig. 1 is a perspective view of a collapsible box-like member used by me as the central portion of my reel.

Fig. 2 illustrates the manner in which the cen-

tral member is rotated to wind ribbon thereon.

Fig. 3 is an exploded view showing the manner in which a flange is assembled to the central member after the ribbon has been wound thereon.

Fig. 4 is a vertical section through the finished reel showing the ribbon wound thereon.

Fig. 5 is a horizontal section through the central member taken in the plane of one of the openings thereof.

Referring now more particularly to the drawing and especially Fig. 1, the central member constituting the central portion of my reel is designated generally by reference numeral 10. This central member is preferably formed of a single piece of some material such as cardboard, and may be assembled into the rectangular box-like form illustrated, with surface portion 11 and a portion 12 in overlapping relationship whereby to strengthen the resulting box. Preferably, end flaps 13 extend at each end of the box and are adapted to be bent over as illustrated in Fig. 1 so that the ribbon may be wound thereon.

In describing my invention, I shall use reference numeral 15 to designate the side surfaces of the box-like central member 10, and I shall term the surface 11 and the equivalent surface 11 on the other side of the box-like member 10, spacer surfaces, because they act to space the two side surfaces 15 from one another. The end flaps 13 are extensions of the surfaces 11. The side surfaces 15 are formed with openings 16 having enlarging slots 17 for a purpose to be indicated presently.

Referring now to Figure 2, I illustrate the manner in which a series of central members 10 are applied to a winding mechanism for winding ribbon thereon. The ribbon, which is designated by reference numeral 18, may be unwound from a series of supply reels (not shown) and wound simultaneously on to several central members 10. The several members 10 are applied to parallel winding pins 19 by the passing of the winding pins 19 through the openings 16 of the side surfaces 15. The winding pins 19 are adapted to rotate with a shaft 20 driven by a pulley 21 and a belt 22, it being obvious that the series of central members 10 will be rotated by the pins and the ribbon wound thereon.

In Fig. 3, a length of ribbon 18 is shown wound on a central member 10, the ribbon held in place by a short piece of pressure adhesive tape 26 that is applied most conveniently before the flanges are assembled to the member 10. One flange 23 is shown in Fig. 3 already applied to one of the

side surfaces 15, while a second flange 23 is shown ready for application to the other side surface 15. This second flange 23 has extending therefrom a pair of tabs 24 each formed with a T head 25, the tabs being preferably cut from the body of flange 23. It is quite obvious to those skilled in the art that if the T heads 25 of the tabs 24 are inserted through the enlarging slots 17 of the openings 16 into the hollow of the central box-like member 10 as illustrated in Fig. 4, the tabs 24 will thereafter be held against movement outwardly of the openings 16 by the relatively constricted nature of the openings 16. In other words, the tabs 24 have a bayonet joint relationship to the openings 16 and slots 17, so that by proper manipulation relatively to the said openings 16, the tabs 24 through the T heads 25 are adapted to prevent separation of the flanges 23 from the central member 10 during normal and usual handling of the finished reel. Of course, by proper manipulation, opposite to that used in applying the flanges, they may be removed.

It may be well to indicate that when the ribbon 18 is wound on the collapsible central box-like member 10, it is not only assembled to the central member, but also holds the central box-like member in its box-like form illustrated in Figs. 1 and 3, and against collapse. As will be quite apparent also, the central member 10 may take various forms, and the side surfaces 15 and spacer surfaces 11 may have varying configurations. It will also be quite apparent that the positions of the openings 16 and the tabs 24 co-operable therewith may be reversed, and the tabs and openings may assume different shapes as may be required due to changes in material or otherwise. It will also be quite apparent that because my flanges are assembled after the ribbon winding operation, that winding operation is facilitated, and it is also possible to secure with greater ease the end of the length of ribbon through the pressure adhesive tape 26.

I believe that the operation of my invention and its desirable features will now be quite apparent to those skilled in the art.

I now claim:

1. In a ribbon reel of the class described, a central box-like member on which ribbon may be wound, opposite side surfaces for said box-like member having openings displaced from their center through which may be inserted winding pins for rotating said box-like member to wind ribbon thereon, finishing flanges for said reel adapted for application to said side surfaces, and tabs formed on said flanges for entry into said openings to secure said flanges to said box-like member.

2. In a ribbon reel of the class described, a central member having opposed side surfaces between which is a spacer on which ribbon is adapted to be wound, said opposed side surfaces having openings displaced from their center through which may be inserted winding pins for rotating said central member to wind ribbon thereon, finishing flanges for said reel adapted for application to said side surfaces, and tabs formed on said flanges for entry into said openings to secure said flanges to said member.

3. In a ribbon reel of the class described, a central member having opposed side surfaces between which is a spacer on which ribbon is adapted to be wound, said opposed side surfaces having openings formed therein, finishing flanges for said reel adapted for application to said sur-

faces, and tabs formed on said flanges for entry into said openings to secure said flanges to said central member.

4. In a ribbon reel of the class described, a central member having opposed side surfaces between which is a spacer on which ribbon is adapted to be wound, finishing flanges for said reel adapted for application to said side surfaces after ribbon is wound on said spacer, and cooperative interlocking portions on each of said finishing flanges and side surfaces, said portions interlocking upon movement relatively to one another into assembled relation whereby to secure said flanges to said central member.

5. In a ribbon reel of the class described, a central member having opposed side surfaces between which is a spacer on which ribbon is adapted to be wound, finishing flanges for said reel adapted for application to said side surfaces, and portions of each of said finishing flanges and side surfaces formed so as to cooperate with one another in the manner of a bayonet joint whereby readily to secure said flanges to said central member.

20 6. In a ribbon reel of the class described a central box-like member on which ribbon may be wound, opposite side surfaces for said box-like member having openings displaced from their center, finishing flanges for said reel adapted for application to said side surfaces, and tabs formed on said flanges for entry into said openings to secure said flanges to said box-like member.

35 7. In a ribbon reel of the class described, a central member having opposed side surfaces between which is a spacer on which ribbon is adapted to be wound, said opposed side surfaces having each a pair of opposed openings, each of said openings having a wide portion and a constricted portion, finishing flanges for said reel having tabs of such shape as to enter said openings thru the wide portions thereof, and thereafter to be held by said constricted portions against movement out of said openings.

40 8. In a ribbon reel of the class described, a central member having opposed side surfaces between which is a spacer on which ribbon is adapted to be wound, said opposed side surfaces having each a pair of opposed openings, each of said openings having a wide portion and a constricted portion, finishing flanges for said reel having tabs of such shape as to enter said openings thru the wide portions thereof, after which the movement of said tabs positions them so that they are retained by said constricted portions against movement out of said openings.

45 9. In a ribbon reel of the class described, a central member on which said ribbon is wound, opposed side surfaces for said central member, finishing flanges adapted for application to each of said side surfaces, the said finishing flanges and side surfaces having cooperating tabs and openings formed thereon and with the tabs entering the openings to hold the flanges assembled to the side surfaces.

50 10. In a ribbon reel of the class described, a central member on which said ribbon is wound, opposed side surfaces for said central member, finishing flanges adapted for application to each of said side surfaces, the said finishing flanges and side surfaces having cooperating tabs and openings formed thereon and with the tabs entering the openings to hold the flanges assembled to the side surfaces, said tabs and openings being shaped for cooperation and assembly in 55 the manner of a bayonet joint.

11. In a ribbon reel of the class described, a central member on which said ribbon is wound, opposed side surfaces for said central member, finishing flanges adapted for application to each of said side surfaces, tabs formed as integral parts of said finishing flanges through the cutting of said tabs from said flanges, said tabs being movable out of the plane of said finishing flanges as by flexing and into openings formed in said surfaces, the tabs when flexed inwardly of said openings holding said finishing flanges attached to said central member.

12. In a ribbon reel of the class described, a central member on which said ribbon is wound,

opposed side surfaces for said central member, finishing flanges adapted for application to each of said side surfaces, headed tabs formed as integral parts of said finishing flanges through the cutting of said tabs from said flanges, said tabs being movable out of the plane of said finishing flanges as by flexing and into openings formed in said surfaces, said openings having an enlarged portion for the entrance of the heads of said tabs and a restricted portion for cooperation with said tabs after the heads of said tabs are in said openings, whereby to hold said finishing flanges attached to said central member.

WILLIAM H. HAWKINS.
